UNITED STATES PATENT OFFICE.

EUGENE S. RYONE, OF BRISTOL, RHODE ISLAND, ASSIGNOR, BY MESNE ASSIGNMENTS,
TO CHARLES A. CARTIER, OF PROVIDENCE, RHODE ISLAND.

AUTOMOBILE TIRE-PUMP.

1,071,628.

Specification of Letters Patent. Patented Aug. 26, 1913.

Application filed September 23, 1912. Serial No. 721,741.

To all whom it may concern:

Be it known that I, EUGENE S. RYONE, a citizen of the United States, residing at Bristol, in the county of Bristol and State 5 of Rhode Island, have invented certain new and useful Improvements in Automobile Tire-Pumps, of which the following is a specification:

This invention relates to an improved air 10 pump adapted to be permanently secured on an automobile and be driven by the engine-shaft thereof, to inflate the tires of the vehicle.

The invention consists, primarily, of two 15 synchronously-driven reciprocating pistons, an inlet valve to admit an air suction between the pistons during their separating movement, and a back pressure valve to deliver the charge to the tire at time of ingo- 20ing movement of the pistons.

The invention consists of the special details of construction and combination of parts, as hereinafter described and claimed.

In the accompanying sheet of drawings, 25 Figure 1 represents a central longitudinal section of my improved air pump, showing position of the pistons at end of suction stroke. Fig. 2 is a similar section, showing the pistons at end of compression stroke, 30 as after charge has been forced to inflate the tire. Fig. 3 is a cross-section of the pump, taken on line $x-x$ of Fig. 2.

Referring to the drawings, in which like reference characters indicate like parts, 35 a designates a horizontally-arranged open-ended cylinder having a base portion a^1 , to receive bolts b , b for securing said cylinder permanently upon the engine-bed of the automobile. The cylinder 40 a has a straight bore therethrough to receive two substantially alike pistons c and d , which are each provided with a spiral groove formed in its peripheral surface and both grooves arranged in a reverse order to one another, as at c^1 , c^1 . On a reduced projecting portion of each cylinder-bolt b is mounted a roller e , to fit within the groove c^1 of each piston. A head piece f is secured by 45 threaded engagement at one end of the cylinder a , and is provided with a journal bearing therethrough to receive a rotary shaft g , which is concentric to the bore of said cylinder. The shaft g projects 50 within the cylinder a and a sleeve 55

g^1 , secured on said shaft, has a sliding fit in a bore d^2 formed concentric through each piston c , d . Each piston c , d has longitudinal flanges d^3 arranged diametrically opposite each other, 60 to fit within slotted openings g^2 formed in the sleeve member g^1 of the shaft g . On the shaft g is made fast a sprocket wheel h which is driven by a chain connection i with a sprocket wheel (not shown,) 65 fast on the engine-shaft. The shaft g in revolving imparts a reciprocating motion to the pistons, by means of the fixed rollers e , e moving in the spiral formations of the latter, and the pistons are caused to slide on the flanges d^3 and meet together at each half revolution of said shaft, in the position of parts shown in Fig. 2.

At the upper part of the cylinder a 75 is secured a valve-case j , which has two horizontally-arranged bores provided each with a beveled valve-seat, as k , k^1 , located at either side of an opening j^1 communicating within the cylinder and at 80 a point centrally between the pistons. An inlet disk valve l is provided to close against the seat k , and said valve has a centrally-projecting stem at each side thereof, as l^1 , l^2 , which respectively move 85 in an inlet j^2 formed through the case j , and through the bored hub of a back pressure disk valve m , which is provided to close against the seat k^1 . A 90 collar k^2 has threaded engagement to close one end of the valve-case j , and said collar is provided with two concentric bores n , n^1 , the former bore to center the hub of valve m , and the latter bore to form an outlet for discharge of pressure from the pump; a flexible tube o being employed to convey the pressure to point of inflation of the tire on the vehicle. The outer stem of valve l , and hub of valve m , have each a flat side, as at 95 points l^3 , m^1 , in order to provide sufficient passage for intake and discharge of air to and from the pump. As the pistons start on their outward stroke (Fig. 2,) a suction takes place at the inlet j^2 thereby forcing the valve l from its seat to a point partially closing the opening j^1 , from whence the atmosphere passes and fills the chamber p left by the separating movement of the pistons. After the pistons 100

105

110

perform suction stroke the latter causes the valve —*l*— to instantly close against its seat, and the incoming pistons then cause the pressure to open valve —*m*— and force 5 the charge to the tire.

By this description it is seen I provide a simple, relatively light, and efficient tire pump. The parts are easily assembled and free from liability to derangement, and the 10 valves require no springs to assist in their operation.

Having described my improvements, what I claim and desire to secure by Letters Patent, is:—

15 A tire pump such as described, comprising in combination an air cylinder provided with an intake opening, tubular pistons within said cylinder at each side of the

opening and each piston provided with longitudinal flanges, a rotary shaft concentric to said cylinder, a sleeve secured on said shaft and having slots to receive the flanges of said pistons to permit a working movement of the latter, means for delivering air and preventing return charge of same to 25 said cylinder, means to respectively cause the pistons to separate from each other in making a suction charge and to make compression upon the inclosing movement of said pistons. 30

In testimony whereof I affix my signature in presence of two witnesses.

EUGENE S. RYONE.
